UNITED STATES PATENT OFFICE

MAXIMILIAN M. GOLDBERG, OF DAYTON, OHIO, ASSIGNOR TO THE NATIONAL CASH REGISTER COMPANY, OF DAYTON, OHIO, A CORPORATION OF MARYLAND

AUDITING MACHINE

Original application filed September 7, 1926, Serial No. 134,025. Divided and this application filed January 31, 1930. Serial No. 425,003.

This invention relates to auditing machines of the type disclosed in Letters Patent of the United States No. 1,694,009, granted to Maximilian M. Goldberg, December 4, 1928, and 5 more particularly refers to printing mechanism for such machines.

The subject matter of the present invention forms a division of applicant's co-pending application for Letters Patent of the United 10 States, which has issued into Patent No. 1,818,473, on August 11, 1931.

It is an object of the present invention to provide an improved and a novel impression taking mechanism for auditing machines of 15 the type disclosed in the above referred to patents.

Another object is to provide in a printing mechanism, a hammer retracting member and means carried by the hammer retracting 20 member operating means to trip the hammer.

With these and incidental objects in view, the invention includes certain novel features of construction and combinations of parts, the essential elements of which are set forth 25 in appended claims and a preferred form or embodiment of which is hereinafter described with reference to the drawing which accompanies and forms a part of this specification.

30 In said drawing:

Figs. 1, 2, 4 and 6 correspond to Figs. 133, 134, 135 and 136 in the parent case.

Fig. 1 is a detailed view of the hammer operating and tripping mechanism.

Fig. 2 is a detailed view of the hammer operating means, including the type wheel aligner.

Fig. 3 shows a hammer operating mechanism in the moved position with the retracting means fully retracted, the hammer having been released.

Fig. 4 is a detailed view of the impelling means.

Fig. 5 is a fragmentary view showing the parts in partially restored position at the instant the latch pawl strikes the end of the retracting arm.

Fig. 6 is a fragmentary top plan view of 50 the operating mechanism.

General description

The machine of the parent patent is organized to audit or analyze record strips having control points arranged thereon, representing data appertaining to the several departments of any representative commercial 55 organization.

The record strips may be produced on the machine itself, in a manner set forth in the parent case, or they may be prepared on a machine of the type disclosed in Letters Patent of the United States No. 1,506,056, granted to Maximilian M. Goldberg August 26, 1924. When produced on the machine of this patent, the record strip is known as a "detail 60 record" strip.

When such a detailed record strip is run through the auditing machine of the parent case, the data are analyzed and accumulated 65 on the totalizers according to classification, size, etc. The detail record strips may be prepared in a number of different departments of the same store, or in the several stores comprising the system of chain stores, during a certain period of the business, and 70 then they may be sent to the central office to be run through the auditing machine of the type disclosed in the parent patent for analysis.

After all of the detailed record strips have 75 been run through the auditing machine, the machine may be operated to produce either a summary record strip having control points located thereon in a similar arrangement to those on the detail record strip, or the machine of the parent case may be controlled to produce a printed record known as a grand 80 summary record strip, on which is printed legible characters interpreting the series 85 of control points on the summary record strips.

In addition to printing legible interpretations of the grand summary record, the machine also functions to print interpretative 90 symbols on the detail record and on the summary record strip.

Reference may be had to the parent case for illustrative embodiment of the auditing machine in connection with which the hereinafter disclosed printing mechanism is 100

adapted to be used, and also for facsimile disclosures of the detailed record, summary record and grand summary record strips.

Detail description

5 The mechanism disclosed in the parent patent for printing the indicia on the several records forms the subject matter for the present application and will now be described.

This printing mechanism includes a platen 1953 supported in a channel carried at the free end of an arm 1954 fast on a shaft 1955, suitably supported in a frame 195 (Fig. 6) 15 and which is adapted to be first retracted and then released and thrown sharply against the group of type carriers, only one, 1875, of which is shown herein, mounted on a rod 1834, to take legible impressions from types 20 carried on the type carriers. The rod 1834 is suitably supported in the frame 195.

Another arm 1956 (Figs. 4 and 6) having its hub secured to the shaft 1955, adjacent the frame 195 carries a stud 1957 which, under 25 the influence of gravity, normally rests in a cradle formed in the free end of an arm 1958 of a bell crank, pivoted on the shaft 1955. A spring 1961 normally presses the end of the other arm 1959 of the bell crank, 30 against a shaft 1963, suitably supported in the frame 195, and in another frame not shown herein.

A shoulder 1970 on a coupling pawl 1969, 35 pivotally carried on the free end of an arm 1968 journaled on the shaft 1955 is normally held by a spring 1971 in co-operative relation with a shouldered block 1965 secured to the free end of an arm 1964 pivoted on the shaft 1955 and joined to the arm 1958 by a hub.

40 An arm 1967 projecting downwardly from the arm 1968 is provided with teeth meshing with teeth on the end of an arm 1974 of a lever journaled on the shaft 1963, and a stud 1976 on the other arm 1975 of the lever projects into a cam groove 1652 in the side of the 45 gear 1650 rotatably supported on a shaft 1651, suitably supported in the machine. Any suitable means may be employed to rotate the gear 1650 one complete counter-clockwise rotation at each total taking operation of the machine, to rock the lever comprising arms 1974 and 1975 counter clockwise and then clockwise to normal. As this lever 50 rocks counter clockwise, the toothed end of the arm 1974 meshing with the toothed segment arm 1967 of the bell crank comprising arms 1967 and 1968 rocks this bell crank clockwise about its pivot on the shaft 1955, and due to the coupling pawl 1969, draws the

55 arm 1964 and arms 1958 and 1959 clockwise therewith, gravity causing the arm 1956 and the hammer arm 1954 to follow, with the stud 1957 still resting in its cradle in the arm 1958.

60 As the movements of these parts progress

in the directions indicated, a finger 1977 projecting from the arm 1974 comes into contact with a stud 1978 on the tail of the pawl 1969 rocking this pawl clockwise about its pivot on the arm 1968, eventually releasing the arm 1964 and the bell crank comprising arms 1958 and 1959 to the action of the spring 1961, which immediately rocks the bell crank and the hammer arm 1954 violently counter clockwise until the movement of the bell 75 crank is arrested by the arm 1959 striking the shaft 1963, at which time the accumulated momentum of the hammer arm 1954, carries it further on its clockwise travel to bring the platen 1953 into sharp contact with the types 80 to take the impressions therefrom, after which gravity, assisted by the rebound caused by the somewhat resilient platen, 1953 restores the hammer to its normal position where the stud 1957 again rests in its cradle 85 in the arm 1958, as viewed in Fig. 4.

At this point in the operation of the machine the several parts, not including the hammer arm 1956, occupy the positions in which they appear in Fig. 3 of the drawing. 90

Continued counter clockwise rotation of the gear 1650 and the cam groove 1652 in the side thereof, rocks the lever 1974 and 1975 clockwise rocking the bell crank comprising arms 1967 and 1968 counter clockwise to carry the latch pawl 1969 therewith. As the finger 1977 recedes in a clockwise direction, it gradually releases the pawl 1969 to the influence of its spring 1971, which rocks the pawl counter clockwise about its pivot, at the same time the arm 1968 is carrying the pawl bodily upwardly toward its normal position. This compound movement of the pawl 1969 brings the face thereof against the shouldered block 1965, at which time the finger 1977 breaks contact with the projection 1978, and continued counter clockwise movement of the arm 1968, under the influence of the arms 1974 and 1975 continues to raise the pawl 1969 upwardly relative to the arm 1964. 100 Shortly before the pawl 1969 arrives in its normal position, the shoulder 1970 thereon passes the shoulder 1966 on the block 1965 whereupon the spring 1971 rocks the pawl further counter clockwise to position the shoulder 1670 thereon above the shoulder 1966 on the block 1965. The parts at the end of the operation occupy the positions in which they appear in Figure 1 of the drawing. 110

Mechanism is operated by the impression hammer operating mechanism to align the printing type wheels 1875.

A series of aligning fingers 1983, only one of which is shown herein, pivoted on a shaft 1982, are adapted to be rocked into co-operative relation with the aligning teeth on the type wheel 1975 to hold them in the position to which they are set. Springs compressed between a spring seat rod, carried 125

between a pair of arms 1984, only one of which is shown herein, on the shaft 1982 and the tail of the aligner pawls 1983, normally press the tails against a stop rod 1985 carried between the arms 1984.

5 A cam arm 1988 (Fig. 2) hubbed to the lever comprising arms 1974 and 1975 is provided with a cam slot embracing a stud 1987 projecting from a pitman 1986 having its upper end pivotally connected to one of the arms 1984 and being bifurcated at its lower end to slide on a collar secured to the shaft 1963.

10 The first movement of the arms 1974 and 1975 under the influence of the cam groove 1652 is counter clockwise, which carries the cam arm 1988 therewith, thrusting the pitman 1986 in the direction of its length away from the shaft 1963 to rock the aligner frame 20 comprising the arms 1984, the spring rod and the stop rod 1985, counter clockwise to engage the several aligner fingers 1983 with their respective type wheels 1875, the pitman 1986 moving the arm 1984 slightly beyond 25 this point to further compress the aligner springs.

15 The restoring movement of the arms 1974 and 1975 and the cam arm 1988 draws the pitman toward the shaft 1963 and disengages 30 the aligner fingers 1983 from the type wheels.

20 While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

40 What is claimed is:

1. In a machine of the class described; the combination with an impression hammer; and type carriers; of means to impel the hammer against the type carriers; means to actuate the impelling means; and means carried by the actuating means and tripped by the actuating means to release the impelling means.

2. In a machine of the class described; the combination with an impression hammer; and type carriers; of means to impel the hammer against the type carriers; means to actuate the impelling means; and a spring actuated pawl carried by the actuating means and tripped by the actuating means to release the impelling means.

3. In a machine of the class described; the combination with an impression hammer; and type carriers; of means to impel the hammer against the type carriers; means to actuate the impelling means; a coupling carried by the actuating means to retract the impelling means; and means on the actuating means to release the impelling means.

4. In a machine of the class described; the

combination with an impression hammer; and type carriers; of means to impel the hammer against the type carriers; a projection on the impelling means; means to retract the impelling means; means on the re-
tracting means to cooperate with the projection to actuate the retracting means; means to actuate the retracting means; and means on the actuating means to withdraw the means on the actuating means from co-
operation with the projection to release the impelling means.

70

75

5. In a machine of the class described; the combination with an impression hammer; and type carriers; of means to impel the hammer against the type carriers; a projection on the impelling means; means to retract the impelling means; a releasable coupling between the impelling means and the retracting means; means to actuate the retracting means; and means on the actuating means to uncouple the impelling means from the retracting means.

80

6. In a machine of the class described; the combination with an impression hammer; and type carriers; of means to impel the impression hammer against the type carriers; means to retract the impelling means; means carried on the retracting means to releasably couple the retracting means and the impelling means; means to drive the retracting means; a projection on the coupling; and means on the driving means to uncouple the impelling means from the retracting means.

90

95

7. In a machine of the class described, the combination of an impression hammer, type carriers, means for impelling the hammer against the type carrier, actuating means for said impelling means, and a spring actuated pawl carried by said actuating means and tripped thereby for releasing the impelling means.

100

8. In a machine of the class described, the combination of an impression hammer, type carriers, means for impelling the hammer against the type carrier, a projection on said impelling means, a pawl adapted to cooperate with said projection, a member carrying said pawl for operating said impelling means, and an actuator for said member adapted to trip said pawl for releasing said impelling means from the retracting means.

110

9. In a machine of the class described, the combination of an impression hammer, type carriers, means for impelling the hammer against the type carrier, a projection on said impelling means, a pawl adapted to cooperate with said projection, a member carrying said pawl for operating said impelling means, and a segment for operating said member having an arm adapted to trip said pawl for releasing said impelling means.

115

120

125

10. In a machine of the class described, the combination of an impression hammer, type carriers, means for impelling the ham-

130

mer against the type carrier, a projection on said impelling means, a pawl adapted to co-operate with said projection, a member carrying said pawl for operating said impelling means, and a segment for operating said member having an arm adapted to move into the path of said pawl thereby releasing said impelling means.
